CLAIM

The ornamental design for a stair nosing as shown and described.

DESCRIPTION

FIG. 1 is a front perspective view of a stair nosing according to the present application.

FIG. 2 is a left view of the stair nosing of FIG. 1.

FIG. 3 is a front view of the stair nosing of FIG. 1.

FIG. 4 is a right view of the stair nosing of FIG. 1.

FIG. 5 is a rear view of the stair nosing of FIG. 1.

FIG. 6 is a top view of the stair nosing of FIG. 1; and, FIG. 7 is a bottom view of the stair nosing of FIG. 1.

The broken lines shown in the figures are for the purpose of illustrating portions of the stair nosing and form no part of the claimed design.

The stair nosing is shown with symbolic breaks in its length. The appearance of any portion of the article between the break lines form no part of the claimed design.
